PUMP CONSTRUCTION

David Samiran, Osborn, Ohio

Application July 30, 1943, Serial No. 496,693

5 Claims. (Cl. 103—126)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to pumps, and more particularly, to fluid sealing means for rotary pumps of the impeller type, and has for an object the provision of labyrinth fluid sealing means to prevent or reduce to a minimum the leakage of the fluid being pumped, increasing the volumetric output of the pump with a minimum degree of friction between the rotary parts of the pump and the pump casing.

A further object is the provision of capillary fluid collection sealing means for rotary impeller pumps, formed in the inner surface of the pump casing so that the impeller or rotor means may be disposed to move in juxtaposed closely spaced relation to the inner surface of the pump housing without frictional contact between the rotor and interior of the casing, the sealing means reducing the fluid leakage between the rotor and the inlet and outlet sides of the pump, thus effecting ease of operation, efficiency in the fluid delivery output of the pump, and economy in the manufacture, since the inner wall of the casing and peripheral portions of the impeller means are out of actual contact, a minimum amount of machining operations only are necessary in the manufacture or the assembly of the pump.

Other objects and advantages of the invention will be apparent, as set forth in the following description, taken in connection with the accompanying drawings, in which like reference characters refer to like parts in the several figures.

Fig. 1 is a vertical sectional view taken through a rotary impeller type fluid delivery pump having my improved labyrinth fluid sealing means incorporated therein, certain of the parts being shown in elevation.

Fig. 2 is a cross sectional view through the pump shown in Fig. 1, certain of the parts thereof being shown more or less in elevation.

In the drawings, the numeral 1 indicates a pump casing or housing, as best seen in Fig. 1, having spaced semicylindrical side walls 2 and 3, and parallel end walls 4 and 5, the end wall 5 comprising one face of the removable closure or cover plate 6, which is secured to the housing proper by suitable fastening means, such as cap screws 7.

Referring now to Fig. 2, the housing is provided with substantially aligned fluid inlet and outlet ports 8 and 9, opening into the casing be-

tween the ends of the semicylindrical side walls 2 and 3, and inlet and outlet screens 10 and 11 are disposed across the aforementioned ports to prevent the passage of foreign matter through the pump.

2 A flanged fluid supply nipple or hose connection 12 is secured across the inlet port, and a threaded outlet flange 13 is similarly secured across the outlet port by suitable fastening means, as indicated at 14.

10 Supporting feet, or standards 15, are formed on the base of the pump housing, which may be suitably recessed and threaded to secure the pump in a suitable fixed position for use as desired.

15 The semicylindrical inner side walls 2 and 3 have their central axes at vertically spaced points, as indicated at 16 and 17, and the inner arcuate surfaces of the semicylindrical walls are 20 provided with a plurality of equally spaced, substantially parallel capillary fluid collection sealing grooves 18, terminating just short of the opposite end walls 4 and 5. These end walls 4 and 5 are also provided with a plurality of capillary fluid collection sealing grooves 19, extending radially from the axial centers 16 and 17, in alignment with the parallel grooves 18 aforesaid, and terminate just short of the semicylindrical surfaces aforesaid.

25 30 The inner, or integral end wall 4 of the housing is apertured at spaced points on the axis 16 and 17, best seen in Fig. 1, to form antifriction bearing sockets or openings 20 and 21. The closure plate, or opposite end wall portion 5 is also 35 similarly recessed, as indicated at 22 and 23, to form a second set of antifriction bearing sockets, which also have their centers concentric to the axes 16 and 17. Suitable grease gun fittings of the "Zerk" type are provided for introducing lubricant into the last mentioned recesses.

40 45 A vent opening 25 is formed in the end wall 4, adjacent the outer port 8 to permit the passage of fluid through this wall into the gear casing, later to be described.

50 Interengaging impeller members, indicated generally at 26 and 27, are provided, as seen in the drawings, these impellers being constructed in substantially the same manner, with the exception of the driving gear arrangement, and the same reference numerals are therefore applied to most of the detail constituent parts of both impellers. Each of the impellers is provided with stub axle shafts 28 and 29, extending 55 from the ends thereof, on which are mounted

antifriction bearing means 30 and 31, seated in the respective sockets 20 and 22 and 21 and 23, in the end walls of the pump housing. The central portion of the impellers consists of cylindrical barrels 32 and 33, from the ends of which project the stub axle shafts 28 and 29. Each barrel has secured to the opposite sides thereof, in diametrically opposite relation, a pair of T-shaped impeller heads or blades 34, having arcuate peripheral surfaces 35 arranged to move in closely spaced juxtaposed relation to the interior semi-cylindrical side wall surfaces 2 and 3 of the housing 1. These head members 34 are secured in place on the cylindrical barrels 32 and 33 by pins or rivets 36, and the headed ends 37 of the rivets are secured in flush relation with respect to the arcuate peripheral surfaces 35 of the said heads or blades 34.

Each of the cylindrical barrels 32 and 33 is provided with a longitudinally extending eccentrically mounted grease delivery tube 38 extending from a point adjacent the face of the antifriction bearing 31, so that grease forced under pressure through the fittings 24 may be delivered to both sets of antifriction bearing members. The upper stub axle shaft 28, as seen in Fig. 1, extends through and beyond the end wall 4, and carries fixed thereon a large drive gear 39, and a similarly fixed smaller driving gear 40. The lower stub axle shaft 29 also has fixed thereon a second large gear 41, meshing with the aforementioned gear 39, and identical in size to the last mentioned gear.

The two rotors 26 and 27 are disposed with their impeller blades or heads 34 in a 90° out-of-phase relation so that the arcuate surface 35 of one of the blades will always be in alternately light wiping contact with the cylindrical surface of one of the barrels 32 or 33 of the opposite impeller member, and the two large gears 39 and 41 maintain this relatively fixed out-of-phase interengaging pumping relation between the two impellers.

It will be noted that as the peripheral surfaces 35 rotate past the grooves 18, and as the head members 34 rotate past the grooves 19, the entire length of the capillary grooves 18 and 19 come again in contact with the fluid being pumped, and that the entire length of each capillary groove is completely filled immediately prior to the passing of the rotors.

A cover plate or bell-shaped gear housing closure 42 is suitably secured, as indicated at 43, to the integral side wall portion 4 of the pump housing, and this closure is provided with an integral sleeve extension 44, through which extends the drive shaft 45, mounted on the needle or roller bearings 46 and 47, carried in the sleeve extension. Grease gun fittings 48 are provided to supply lubricant to the needle bearings, and a suitable packing gland member 49 is interposed between the bearings 46 and 47 to prevent leakage from the casing of the fluid being pumped. The end of the drive shaft 45 extending into the bell-shaped gear housing to a point adjacent the lower large gear 41 has fixed thereon a large driving gear 50 meshing with the small driven gear 40 on the upper impeller stub axle shaft 29. An operating handle 51 is secured to the end of the drive shaft 45, projecting through the sleeve extension 44 to the exterior thereof.

By utilizing the capillary fluid sealing grooves in the arcuate side and parallel end walls of the housing, I provide an effective fluid collection labyrinth seal between the inlet and outlet ports

so that the impellers 26 and 27 may be constructed with a free running fit with respect to the end and semicylindrical side walls of the housing, with a relative clearance therebetween of as much as a thousandth of an inch. This makes it possible to reduce the degree of precision machining of parts which is necessary where the parts are in the usual actual wiping contact, and the labyrinth fluid sealing structure reduces leakage between the 10 inlet and outlet ports past the impellers to a minimum, thus providing a pump structure that is extremely efficient in its volumetric output, and operable with a minimum degree of friction and effort. The pump is entirely enclosed and substantially frictionless with the exception of the slight wiping contact between the arcuate surfaces of the rotors, and the friction of the packing or sealing gland 49 on the drive shaft 45. While I have described the pump as operating with definitely located inlet and outlet ports, it is obvious that the pump is fully reversible by merely turning the crank handle in the opposite direction.

For the actual operation of the impellers of the pump, reference may be had to Patent 2,262,231, issued on November 11, 1941 to F. W. Guibert, et al., which discloses a rotary impeller pump of somewhat conventional form, having impeller heads or blades similar in general shape to that disclosed in my improved pump. In this patent, 20 the periphery and ends of the impeller blades are arranged to move in wiping contact with the end and side walls of the pump housing, requiring precision machining of parts in order to reduce leakage, and the relative friction between these 30 parts is sufficient to make a pump of this type, without my improved construction incorporated therein, very difficult to operate, which soon causes inefficiency in fluid delivery output as the 35 parts become worn, due to this friction.

Having thus described a specific embodiment 40 of my invention for illustrative purposes, what I claim as new, and desire to secure by Letters Patent, is:

1. In a rotary fluid pump casing for impeller 45 pumps of the class described, a closed casing having parallel end walls and a pair of spaced semicylindrical side walls facing each other with substantially aligned inlet and outlet ports formed in the casing intermediate the adjacent ends of 50 the curved surfaces of the semicylindrical walls, said semicylindrical walls having a plurality of spaced substantially parallel capillary fluid collection grooves formed therein extending without interruption in their length substantially longitudinally to the axes of the semicylindrical walls to 55 points adjacent to and spaced from each of the parallel end walls of the casing.

2. A rotary fluid pump casing for pumps of the 60 class described, comprising a closed casing having parallel end walls and a pair of spaced semicylindrical side walls facing each other with substantially aligned inlet and outlet ports formed in the casing intermediate the adjacent ends of the curved surfaces of the semicylindrical walls, said semicylindrical walls having a plurality of spaced 65 substantially parallel capillary fluid collection grooves formed therein extending without interruption in their length substantially longitudinally to the axes of the semicylindrical walls to 70 points adjacent to and spaced from each of the parallel end walls of the casing, said parallel end walls having a plurality of spaced capillary fluid collection grooves formed therein and extending substantially radially outward from the axial center of the semicylindrical walls of the casing to 75

ward the parallel fluid collection grooves formed in the semicylindrical side walls of the casing and terminating at points adjacent to and spaced radially inwardly from each of the semicylindrical side walls to leave adjacent unobstructed end and side wall portions at the juncture between the semicylindrical side walls and each of the parallel end walls, extending between the adjacent inlet and outlet ends of the casing.

3. In a rotary fluid pump of the class described, a closed casing having parallel end walls and a continuous intermediate wall comprising a pair of spaced semicylindrical side walls facing each other with intermediate connecting walls having substantially aligned inlet and outlet ports formed therein intermediate the adjacent ends of the curved surfaces of the semicylindrical walls, said semicylindrical walls having a plurality of substantially parallel capillary fluid collection liquid sealing grooves formed therein between the ends thereof extending substantially parallel to the axes of the semicylindrical walls, each groove terminating at its ends adjacent the adjoining parallel end walls of the casing in spaced relation thereto, said parallel end walls having a plurality of capillary fluid collection grooves formed therein and extending substantially radially outward from the axial center of the semicylindrical walls of the casing in radial planes passing through the capillary grooves formed in the inner semicylindrical surfaces of the casing and terminating in radially inwardly spaced relation to the first mentioned grooves, and interengaging rotary impeller pumping means within the casing operable in closely spaced relation to said side and end walls past said capillary fluid collecting grooves and the ungrooved portions of the side and end walls intermediate the adjacent ends of the grooves in the end and side walls.

4. In a rotary fluid pump casing for pumps of the class described, a closed casing having parallel end walls and a pair of spaced semicylindrical side walls facing each other with substantially aligned inlet and outlet ports formed in the casing intermediate the adjacent ends of the curved surfaces of the semicylindrical walls, said semicylindrical walls each having a plurality of substantially parallel capillary fluid collection liquid sealing grooves formed therein extending substantially equally spaced around the walls between the ends thereof parallel to the axes thereof to points adjacent to and spaced from the adjoining parallel end walls of the casing, said parallel end walls having a plurality of capillary fluid collection grooves formed therein and extending substantially radially outward from the axial center of the semicylindrical walls of the casing in radial planes passing through the capillary sealing grooves formed in the inner semicylindrical surfaces of the casing, said longitudinal and radial sealing grooves having their adjacent ends terminating opposite each other in spaced relation to leave the adjoining side and end wall portions of the casing uninterrupted.

5. In a rotary fluid pump of the class described, a closed casing having parallel end walls and a

pair of spaced semicylindrical side walls facing each other with substantially aligned inlet and outlet ports formed in the casing intermediate the adjacent ends of the curved surfaces of the semicylindrical walls, said semicylindrical walls having a plurality of substantially parallel capillary fluid collection liquid sealing grooves formed therein extending substantially longitudinally of the semicylindrical walls parallel to the semicylindrical walls to points spaced from and adjacent to the adjoining parallel end walls of the casing, said parallel end walls having a plurality of capillary fluid collection grooves formed therein and extending substantially radially outward from the axial center of the semicylindrical walls of the casing in planes passing through the capillary grooves formed in the inner semicylindrical surfaces of the casing, terminating adjacent to and radially inwardly of the semicylindrical side walls, and interengaging rotor impeller fluid pumping means journaled in the casing in said parallel end walls with their axes concentric to the radial centers of the semicylindrical walls of the casing and having spaced substantially similar arcuate surfaces arranged to move past the aforesaid substantially parallel capillary fluid collection liquid sealing grooves in closely spaced relation to the semicylindrical walls aforesaid, between the inlet and outlet ports in the casing, said interengaging rotary impeller fluid pumping means having parallel end surfaces adjoining the arcuate surfaces thereof and disposed to move past the substantially radially disposed capillary fluid collection grooves in the parallel end walls of the casing in closely spaced fluid sealing relation thereto, with the edges of the impellers at the juncture between the arcuate surfaces and the adjacent parallel end walls disposed to move in closely spaced relation past the adjacent ungrooved portions of the casing located between the adjacent ends of the parallel fluid collection liquid sealing grooves and the outer ends of the radially disposed capillary fluid collection grooves.
